DESIGN FOR A CORNER TRIMMER FOR CARDS OR SIMILAR ARTICLES

Jorgen C. Andersen, Rochester, N. Y., assignor of three-fourths to Theodore Christie, Rochester, N. Y.

Application October 2, 1935, Serial No. 58,802

Term of patent 14 years

To all whom it may concern:

Be it known that I, Jorgen C. Andersen, a citizen of the United States, residing at Rochester, in the county of Monroe and State of New York, have invented a new, original, and ornamental Design for a Corner Trimmer for Cards or Similar Articles, of which the following is a specification, reference being had to the accompanying drawing, forming a part thereof.

trimmer for cards or similar articles looking at it from the front, showing my new device.

I claim:

The ornamental design for a corner trimmer for cards or similar articles as shown.

JORGEN C. ANDERSEN.
